UNITED STATES PATENT OFFICE.

THEODORE S. SAVAGE, OF OAKLAND, CALIFORNIA.

SIGNAL FOR AUTOMOBILES.

1,283,569.

Specification of Letters Patent. Patented Nov. 5, 1918.

Application filed September 30, 1915. Serial No. 53,209.

To all whom it may concern:

Be it known that I, THEODORE S. SAVAGE, a citizen of the United States, residing at Oakland, in the county of Alameda and State of California, have invented certain new and useful Improvements in Signals for Automobiles, of which the following is a specification.

This invention relates to improvements in signals particularly adapted for use on motor vehicles, the principal object of my invention being to provide a signal to indicate in which direction the vehicle is about to turn, which is light in weight, simple in construction, and which has no moving parts.

Another object of my invention is to provide a signal, which may be noted in daylight as well as by night, which can be combined with a tail light, and which may be installed without much trouble on any motor vehicle.

With these and other objects in view my invention consists in the novel construction, combination and arrangement of parts herein described and more specifically pointed out in the appended claims.

Reference being had to the accompanying drawings forming a part of this specification,

30 Figure 1 is a view in elevation showing my improved signal with the glass covering partly broken away.

Fig. 2 is a view in end elevation.

Fig. 3 is a view in section on the line 3—3,

35 Fig. 1.

Fig. 4 is a diagrammatic view illustrating the structure used in connection with the signal.

Referring to corresponding parts in the 40 several views by the same numerals of reference, 1 denotes a metal case preferably rectangular in shape and having flanged outer edges 2, and 3 denotes a removable end plate.

45 Seated within the case 1 is a block 4, of wood or other insulating material forming a base to which certain division walls 5 are attached. These walls consist of the curved members 6 and 7, symmetrically disposed 50 within the casing and extending in opposite direction from the end plates of the casing to the top and bottom walls thereof. These members are joined adjacent the top and bottom of the case 1, to other curved members 8 and 9 extending to the other end wall adjacent the end of members 7 and 6 re-

spectively. These members are so shaped that members 6, taken in connection with members 8 and members 7 taken in connection with members 9 form the outlines of two arrows pointing to the left and right respectively. The recesses formed by these members are quite deep in comparison with a width and the sides and bottoms are painted black so that certain lamps placed therein are visible by day as well as by night.

In the preferred embodiment of my invention I provide five lamps denoted by 10 arranged in a line through the horizontal axis 70 of these arrows and additional lamps 11 in the compartments 12 formed between divisional walls 6, 7 and 9 and lamps 13 in the compartments 14 formed between the division walls 6, 7 and 8. The base plate 4 is 75 provided with recessed openings 15 in which are seated the lamp sockets 16. The various sockets being connected by suitable wiring shown diagrammatically in Fig. 4. On the back of the case 1 is provided means 17 by 80 which the device may be attached to the rail lamp bracket, or other suitable supporting structure.

I prefer to provide a tail light 18 mounted on the top of casing 1 so that all signal apparatus may be associated together in one position on the car. This light contains the usual parabolic reflector and electric lamp 29.

In mounting the device on the car I provide two switches, one of which closes a circuit to lamps 10 and 11, the other of which closes a circuit to lamps 10 and 13.

Thus when the signal is installed on a car and it is desired to turn to the left, that switch is moved which allows current to 95 flow through lamps 10, and lamps 13, illuminating the center compartments and compartments 14 outlining an arrow pointing to the left. On the other hand, if the other switch is moved the lamps in the center compartment are illuminated together with those of compartments 12, outlining an arrow pointing to the right indicating to a following vehicle that the car is about to turn to the left or right as either switch 18 or 19 is 105 moved. If both switches are closed a double ended arrow is the result, which indicates that the vehicle is about to stop.

While I have shown the preferred embodiment and construction of my invention it will be understood that minor changes may be made in form and details of construction

without departing from the scope of the claims.

What I claim and wish to cover by Letters Patent is:—

- 5 1. A signal device of the character described, comprising a base, division walls extending outwardly therefrom, said walls forming a central, substantially rectangular compartment bounded by two pair of side compartments its full length, whereby a pair 10 of said side compartments taken selectively and in conjunction with said central compartment, form an arrow.
2. A signal device of the character described, comprising a base, division walls extending outwardly therefrom, said walls forming a central, substantially rectangular compartment bounded by two pair of side compartments its full length, whereby a pair 15 of said side compartments taken selectively and in conjunction with said central compartment, form an arrow, and means to illuminate said central compartment in conjunction with either or both pair of said side compartments.
3. A signal device of the character described, comprising a rectangular casing enclosing partition walls, said walls blocking out a central, longitudinal compartment,

bounded by symmetrically disposed side compartments, whereby said central compartment in conjunction with a pair of directly opposed side compartments, form a stem and arrow-head.

4. A signal device of the character described, comprising a rectangular casing enclosing partition walls, said walls blocking out a central, longitudinal compartment, bounded by symmetrically disposed side compartments, whereby said central compartment in conjunction with a pair of directly opposed side compartments, form a stem and arrow-head, and means to illuminate said stem and arrow-head.

5. In an automobile signal device, a compact unit structure, comprising a tail-lamp and a rectangular casing, said lamp mounted centrally on said casing, said casing provided with a longitudinal compartment forming the stem of an arrow, and a plurality of triangular compartments adjacent to the sides thereof forming the barbs of an arrow-head, lamps within said compartments, and means to selectively illuminate said signal device.

In testimony whereof I affix my signature

THEODORE S. SAVAGE.
